UNITED STATES PATENT OFFICE.

HEBON B. LAYMAN, OF NEW YORK, N. Y.

INTERNAL-COMBUSTION ENGINE.

1,144,423.

Specification of Letters Patent. Patented June 29, 1915.

Application filed July 15, 1914. Serial No. 851,026.

To all whom it may concern:

Be it known that I, HEBON B. LAYMAN, citizen of the United States, and residing at New York, in the county of New York and State of New York, have invented certain new and useful Improvements in Internal-Combustion Engines, of which the following is a specification, such as will enable those skilled in the art to which it appertains to make and use the same.

This invention relates to explosion or internal combustion engines, and particularly the engines of this class of the sleeve valve type, and the object thereof is to improve the construction of, and the method of assembling the parts of engines of this class, so as to facilitate the finishing and assembling of said parts and render the same more practical and economical and at the same time increase the efficiency of such engines; and with this and other objects in view the invention consists in the construction and arrangement of parts hereinafter described and claimed.

25 This invention is applicable to engines of the class specified, comprising any desired number of units or cylinders, and said invention is fully disclosed in the following specification, of which the accompanying drawing forms a part, in which the separate parts of my improvement are designated by suitable reference characters in each of the views, and in which:

Figure 1 is a central vertical transverse section through one cylinder of an engine involving my invention; and, Figs. 2 and 3 similar views but showing modifications.

In carrying my invention into effect, as shown in Fig. 1, each unit of the engine is composed of four separate parts, namely, the cylinder *a* and its inclosing jacket or casing *a*², the explosion head *b* containing the explosion chamber *b*², the manifold casing *c* containing the inlet and exhaust manifolds *c*² and *c*³ which are inclosed by an outer casing or jacket *c*⁴, and a cap *d*, and these four parts are formed separately.

The cylinder *a* and its inclosing jacket or casing *a*² are provided with a top horizontal flange *a*³ and the explosion head *b* is provided with a bottom horizontal flange *b*³ which rests on the flange *a*³ and is secured thereto in any desired manner and above the flange *b*³ the explosion head *b* is also provided with another horizontal flange *b*⁴ on which the manifold casing *c* rests, and said

manifold casing *c* is provided with a bottom flange *c*⁵ which corresponds with the flange *b*⁴ and rests thereon.

The body of the explosion head *b* is cylindrical in form and the manifold casing *c* is also cylindrical in form, and these parts form an annular valve casing *e* in which is an annular valve chamber *e*² in which is a sleeve valve *e*³ which controls the inlet and exhaust ports or passages *c*⁶ and *c*⁷ of the inlet and exhaust manifolds *c*² and *c*³.

The explosion chamber *b*² which communicates with the cylinder *a* is smaller in transverse dimensions than the main body part of said explosion head and the walls *b*⁵ of said explosion chamber are flared at the bottom as shown at *b*⁶, and said explosion chamber is placed in communication with the inlet and exhaust manifolds *b*⁷, and said explosion chamber or the walls thereof are inclosed by a water chamber or passage *f* having at the bottom a horizontal circular extension *f*² and the cylinder *a* and its inclosing jacket or casing *a*² form a main water chamber or passage *g* which is placed in communication with the water chamber or passage *f* by ports or passages *h* while the water chamber or passage *f* is placed in communication with the cap *d* by ports or passages *h*².

The inner wall of the manifold casing *c* and its inclosing casing or jacket *c*⁴ form a water chamber or passage *i* which incloses the manifolds *c*² and *c*³ and is placed in communication at the bottom thereof with the water chamber or passage *f* by ports or passages *h*³ and with the cap *d* by ports or passages *h*⁴, and with this construction, when the engine is in operation, the water from the radiator enters the bottom of the chamber or passage *g* in the usual manner and flows upwardly through both the chambers or passages *f* and *i* into the cap *d* and from said cap it flows back to the radiator in the usual manner, and there is therefore a continuous flow of water upwardly on both the inner and outer sides of the valve chamber or its casing and around the manifolds *c*² and *c*³.

Arranged centrally of the cap *d* and in the top of the explosion head *b* is a chamber or recess *j* which is placed in communication with the explosion chamber *b*² by a threaded passage *j*² into which the spark plug, in practice, is screwed, but as said spark plug

forms no part of this invention it is not shown.

This construction facilitates the formation of all the parts which may be cast separately, as will be readily understood, and the machining and finishing of said parts, and of the walls of the valve chamber, and renders the said operation or operations more simple and effective, and at the same time more economical than is usual in this class of engines, and the circulation, or method of circulating the cooling water is most practical and effective in retaining the parts which are apt to become overheated at the lowest possible degree of temperature.

The cap *d* is not an absolutely essential feature in this construction as other means may be provided for returning the cooling water after it passes through the explosion head and the manifold casing of the engine.

In the construction shown in Fig. 2, the explosion chamber *b*² is made larger transversely and there is no water chamber or passage between the explosion chamber, or 25 the walls thereof, and the valve casing *e* or the chamber *e*² in which the valve *e*³ operates is formed by the walls of the explosion chamber *b*² and the main part of the manifold casing *c*. The manifold casing 30 *c*, the manifolds *c*² and *c*³, and the manifold jacket or casing *c*⁴ are substantially the same, in the form of construction, as in Fig. 1, and the base flange *b*⁴ of the explosion head *b* rests directly on the top or 35 flange *a*³ of the cylinder *a* and its inclosing casing or jacket *a*², and the water chamber or passage *i* in the manifold casing *c* is placed in communication with the water chamber or passage *g* by ports or passages *h*, 40 as in Fig. 1, and said water chamber or passage *i* is placed in communication with the cap *d* by ports or passages *h*⁴ as in Fig. 1. In this form of construction the chamber or 45 recess *j* in the cap *d* and the top of the explosion head is made deeper than in Fig. 1, or extends downwardly into the explosion head farther, and around the bottom portion of said chamber or recess *j* and within 50 in the explosion head is a water passage or chamber *k* which is in communication with the cap *d* by means of ports or passages *h*² as in Fig. 1. With this construction the water circulates only around the cylinder or 55 upwardly through the water chamber or passage *g* and upwardly into and through the water chamber or passage *i* and around the manifolds *c*² and *c*³ and into the cap *d* from which it passes into and out of the 60 chamber or passage *k*, but there is no continuous flow of water inside and outside the water chamber or its casing as in Fig. 1.

In the construction shown in Fig. 3, the manifold casing *c* has no water jacket or casing and the manifolds *c*² and *c*³ are exposed but there is a free circulation of water

upwardly through the chamber or passage *g*, around the cylinder *a*, into and through the explosion head *b* and into the cap *d*, said explosion head being provided inwardly of the valve casing with a water chamber or 70 passage *f* similar in all respects to the water chamber or passage *f* in Fig. 1. As with the construction shown in Fig. 1 the cap *d* in Figs. 2 and 3 is not absolutely essential 75 as the water from the explosion head may be conveyed to the radiator by other means. From the foregoing description, it will be seen that the chief and essential characteristics are the cylinder *a* with its jacket or casing *a*², the explosion head *b*, and the manifold casing *c* constructed and combined as shown and described, the use of the cap *d* being preferred, but not essential.

In the accompanying drawing no means for operating the valve *e*² is shown, but it 85 will be understood that said valve may be operated in the usual manner, or by any preferred means, such for instance as that shown and described in U. S. Letters Patent No. 1,063,082, May 27, 1913, and No. 1,017,073, 90 Feb. 13, 1912.

Having fully described my invention what I claim as new and desire to secure by Letters Patent, is:—

1. In an explosion engine, a cylinder having a main outer jacket or casing, an explosion head detachably mounted on said cylinder and casing, and a detachable manifold casing inclosing the explosion head and between which and said explosion head is a 95 sleeve valve casing formed partly by said explosion head and partly by said manifold casing.

2. In an explosion engine, a cylinder provided with a main outer casing or jacket, an explosion head detachably mounted on said cylinder and jacket and containing the explosion chamber, and a detachable manifold casing inclosing the explosion head and between which and said head is a sleeve valve which 105 controls the inlet and exhaust ports or passages leading to and from the explosion chamber, said sleeve valve casing being formed partly by the explosion head and 110 partly by the manifold casing, and said cylinder and its casing or jacket forming a water chamber or passage which communicates with a water chamber or passage in the explosion head and inclosing the explosion 115 chamber and is provided with an outlet through the top of said head.

3. In an explosion engine, a cylinder provided with a main outer casing or jacket, an explosion head mounted on said cylinder and jacket and containing the explosion chamber, and a manifold casing inclosing the explosion head and between which and said head is a sleeve valve casing provided 125 with a sleeve valve which controls the inlet 130

and exhaust ports or passages leading to and from the explosion chamber, said sleeve valve casing being formed partly by the explosion head and partly by the manifold casing, said cylinder and its casing or jacket forming a water chamber or passage which communicates with a water chamber or passage in the explosion head and inclosing the explosion chamber and is provided with an outlet through the top of said head, and said manifold casing being also provided with an inclosing jacket or casing forming a water chamber or passage which is also in communication with the water chamber or passage in the explosion head below the valve casing and which has an outlet at the top thereof.

4. In an internal combustion engine, a cylinder provided with an inclosing jacket forming a main water chamber or passage, an explosion head detachably mounted on said cylinder and containing the explosion chamber, said head being provided with a supplemental water chamber or passage which incloses the explosion chamber, and which is in communication with the main water chamber or passage, and a manifold casing mounted on and inclosing the explosion head and between which and the explosion head is a sleeve valve casing, a sleeve valve mounted in said casing and controlling the inlet and exhaust ports into and from the explosion chamber, said manifold casing being provided with an outer casing or jacket which incloses the manifolds and which forms an auxiliary water chamber or passage which is in communication with the supplemental water chamber or passage below the sleeve valve casing and a detachable cap mounted on the explosion head and

on the manifold casing and which is in communication with the supplemental water chamber or passage and the auxiliary water chamber or passage.

5. In an internal combustion engine, a cylinder, an explosion head detachably mounted thereon and in which is the explosion chamber and a detachable manifold casing mounted on the explosion head and having inlet and exhaust manifolds, said explosion head and said manifold casing forming a sleeve valve casing in which is mounted a sleeve valve which controls the inlet and exhaust ports or passages between the manifolds and the explosion chamber. 55

6. In an internal combustion engine, a cylinder, an explosion head detachably mounted thereon and in which is the explosion chamber, a detachable manifold casing mounted on the explosion head and carrying inlet and exhaust manifolds, and a detachable cap placed on said head and casing, said explosion head and said manifold casing forming a sleeve valve casing in which is mounted a sleeve valve which controls the inlet and exhaust ports or passages between the manifolds and the explosion chamber, said cylinder being provided with a jacket or casing forming a main water chamber and said explosion head with a supplemental water chamber or passage in communication therewith and with said cap. 70

In testimony that I claim the foregoing as my invention I have signed my name in presence of the subscribing witnesses this 11th day of July, 1914.

HEBROW B. LAYMAN.
